United States Patent Office.

JONATHAN F. BARRETT, OF CONCORD, MASSACHUSETTS.

Letters Patent No. 69,163, dated September 24, 1867.

IMPROVED RUBBER BOOT-HEELS.

The Schedule referred to in these Letters Patent and making part of the same.

TO ALL WHOM IT MAY CONCERN:

Be it known that I, J. F. BARRETT, of Concord, in the county of Middlesex, and State of Massachusetts, have invented an improvement in Attaching Rubber Boot and Shoe-Heels, &c.; and I do hereby declare that the following, taken in connection with the drawings which accompany and form part of this specification, is a description of my invention sufficient to enable those skilled in the art to practise it.

The invention relates particularly to the attachment of boot and shoe-heels, made of rubber or other similar elastic material, or the compounds thereof, to their soles; but it is applicable to other similar purposes in which it is desirable to firmly attach a yielding material to any surface by means of nails driven into the same. The general adaptation of the invention to different purposes will however be clearly understood by the following description of the method of attaching a rubber heel to its seat.

The drawing shows a section of the heel, with that part of the sole to which it is fastened.

Within the rubber or rubber compound a plate, sheet, or strip or metal, or other suitable material, *a*, is inserted, this being preferably effected by placing the plate in the mould in which the elastic heel is formed, and moulding the rubber around it by the common processes of heat and pressure, the plate being left embedded in the rubber in the position it is desirable that it should occupy in the moulded heel.

In fastening the heel to the sole *b* the nails *c* are so driven as to strike the plate *a*, which will turn their points, and cause them to clinch in the surface of the rubber above the plate, as seen in the drawing.

It will be obvious that when so secured the heel cannot be separated from the boot or shoe to which it is applied without tearing away the rubber, and that the resistance offered by the bent or clinching parts of the nails offers sufficient obstacle to prevent the separation of the heel from the boot by wear. Other material than metal may be used for this plate *a*, such material being of sufficient degree of hardness to turn the points of the nails without their penetrating the plate.

Filling of cork or other light material may enter into the construction of the heel, such material not being employed to secure the nails, but for the purposes of lightness and economy. If it be desirable to apply tread-pieces of leather or other hard material to the wearing surface of the heel, the opposite or lower surface of the plate *a* will serve to clinch and fasten the nails driven through such tread-piece into the heel.

I claim the employment of a clinching-plate, of metal or other material, for the purpose of turning the points of nails used in securing elastic parts to the surfaces to which they are to be attached, substantially as set forth.

JONATHAN F. BARRETT.
